CABINET FOR A COIN-CONTROLLED SLOT MACHINE

Paul Belokin, Jr., Berwyn, Ill., assignor to Bally Manufacturing Corporation, Chicago, Ill., a corporation of Delaware

Filed Feb. 2, 1970, Ser. No. 21,216

Term of patent 14 years

Int. Cl. D21—04

U.S. Cl. D34—5

Fig. 1.

Fig. 2.

Fig. 3.

Fig. 4.

FIG. 1 is a perspective view of a cabinet for a coin-controlled slot machine showing my new design;

FIG. 2 is a front elevational view;

FIG. 3 is a right side elevational view; and

FIG. 4 is a top plan view.

The rear is substantially plain and unornamented.

I claim:

The new and ornamental design for a cabinet for a coin-controlled slot machine, as shown and described.
